FOUNDATION GARMENT

Martin Gross, New York, N. Y.

Application April 22, 1938, Serial No. 203,505

1 Claim. (Cl. 2—38)

This invention relates to new and useful improvements in a corset or the like foundation garment.

More specifically, the invention proposes the construction of a corset or the like foundation garment characterized by a strip of cloth material formed from several sections in a longitudinal line for encircling one's body, and which is provided at its adjacent free ends with a novel means 5 for closing the strip of material for holding the same in position upon the body.

Still further it is proposed to characterize the holding means by stationary hook fasteners mounted on the ends of the strip above the horizontal center thereof and by slide fasteners mounted on the ends of the strip below the horizontal center thereof.

Still further it is proposed to provide a means for adjustably connecting together the adjacent 20 back edges of the sections forming said cloth strip for permitting the diameter of said garment to be adjusted so as to be capable of engagement upon different people.

Still further it is proposed to provide a means 25 for adjustably connecting the stringers of the slide fastener to the edge portions of said strips for assisting in controlling the diameter of the garment.

For further comprehension of the invention, 30 and of the objects and advantages thereof, reference will be had to the following description and accompanying drawings, and to the appended claim in which the various novel features of the invention are more particularly set forth.

In the accompanying drawings forming a material part of this disclosure:

Fig. 1 is an elevational view of a corset or the like foundation garment constructed according to this invention.

Fig. 2 is a view similar to Fig. 1 showing the front of the garment in the open position.

Fig. 3 is an enlarged sectional view on the line 3—3 of Fig. 1.

Fig. 4 is an enlarged sectional view on the line 45 4—4 of Fig. 1.

Fig. 5 is a view similar to a portion of Fig. 1 but illustrating a modification of the invention.

Fig. 6 is an enlarged sectional view on the line 6—6 of Fig. 5.

Fig. 7 is a partial rear elevational view of a garment constructed according to a still further modification of the invention.

Fig. 8 is a view similar to Fig. 7 illustrating a further modification of the invention.

The corset or the like foundation garment com-

prises a strip of cloth material 10 for encircling the body. The strip of cloth material is formed from several sections 10^a in longitudinal line. A means is provided for adjustably connecting the back vertical edge portions 10^a in such a manner that the diameter thereof may be adjusted for increasing or decreasing the same to meet various requirements.

The means for adjustably connecting together the back vertical edge portions of the sections 10^a comprises a lace 11 which is adapted to be passed through openings 12 formed along the vertical edge portions of the section 10^a. The lace 11 may be shifted for increasing or decreasing the space between these vertical edge portions of the sections for increasing or decreasing the diameter thereof.

Reinforcement stays are mounted on the strip for supporting portions of one's body. At the top of the strip, elastic members 13 are connected between portions of the strip for compressing the abdomen. Below these elastic members non-elastic material 14 is securely attached at one edge to a portion of the cloth strip 10 and its free edge is connected with an elastic member 15 which in turn has its free edge connected to still another portion of the cloth strip 10 for assisting the corset in shaping and compressing the thighs. Longitudinal bone or spring steel stays 16 are mounted along the vertical length of the garment 30 and are securely attached in position by means of stitches 17.

Garter support elements 18 are securely attached to the bottom edges of the cloth strip material for properly supporting stockings, and still other 35 garter support elements 19 are attached to the non-elastic material 14 at the bottom edge thereof. These support elements 19 also assist in supporting the stockings.

Stationary hook fasteners are mounted on the 40 ends of the sections 10^a forming the cloth strip 10 above the horizontal center of the strip for closing the top portion of the garment. These stationary fasteners are at the front of the garment and comprise strips of rigid material 20 attached 45 to the edge portions of the sections 10^a and upon which the hook fasteners are mounted. Headed studs 21 are mounted on the strip of rigid material at one side of the front opening and are adapted to be engaged by complementary eyelets 50 22 attached to the other strip of rigid material for holding the top portion of the garment in its closed position.

A slide fastener 23 is mounted on the adjacent edge portions of the sections 10^a forming the 55

strip 10 below the horizontal center of the strip for closing the bottom portion of the garment. The slide fastener is characterized by stringer elements 23^a securely attached to the edge portions of the sections 10^a. Hookless fasteners 23^b are mounted on the free edges of the stringers 23^a and a control slide 23^c is provided for engaging and disengaging the hookless fasteners 23^b for opening and closing the said garment.

10 The edge portions of the sections 10^a forming the garment is of double layer material as clearly shown in Fig. 3, and the edge portions of the stringers 23^a are inserted between the layers and extend therefrom. A double layer covering strip 15 24 is securely attached at one of its edges to the edge portion of one of the sections 10^a and is adapted to extend across the back face of the 20 slide fastener in the closed position of the garment for preventing these slide fasteners from 25 coming in direct contact with the body.

The operation of this device is as follows:

The stationary hook fasteners are mounted on the upper ends of the sections of the garment for opening the top portion of said garment 25 and the control slide 23^c of the slide fastener 23 is moved downwards to open the bottom portion of the garment. The garment is then positioned on the body and the eyelets 22 are engaged on the headed studs 21 for closing the 30 top portion of the garment to position the same upon the body. The control slide 23^c is moved to its closed position for closing the bottom portion of the garment and to assist the stationary hook fasteners in properly holding the 35 garment in position upon the body. The garter support elements 18 and 19 may then be engaged with the top of the hose for also holding these in their proper position.

According to the modification shown in Figs. 40 5 and 6, a means is provided for adjustably connecting the stringers 23^a of the slide fastener 23 with the edge portions of the sections 10^a forming the cloth strip 10 for permitting the diameter of the bottom portion of the garment to be increased or decreased as desired.

45 This means includes the stringers 23^a which are provided with openings 25. The edge portions of the stringers 23^a are inserted between the double layer of material 26 which is free 50 at its adjacent edge portions for forming a pocket into which the free edge of the stringers may be engaged. A portion 10^{aa} of the sections 10^a forming the garment extend into the pockets 26 formed by the double layer of material. This 55 inwardly extending portion 10^{aa} is provided with a vertical line of openings 27 arranged in aligned positions with the openings 25. A lace 28 is adapted to be passed through the openings 25 and 27 for connecting the stringers 23^a to the 60 edge portions of the sections 10^a and is capable of being adjusted for increasing the space between the adjacent edge portions of the stringers 23^a and the section 10^a for increasing the diameter of the bottom portion of the garment.

Thus when the garment is positioned upon the body and it is found that the bottom portion thereof is too tight, the diameter thereof may be increased by bending the panels forming the pocket 26 back to permit 5 the lace 28 to be adjusted to increase the space between the adjacent edge portions of the stringers 23^a and the section 10^a. In other respects this form of the invention is similar to the previous form. 10

According to the modification shown in Fig. 7, the adjacent back edge portions of the sections 10^a forming the cloth strip 10 are fixedly connected together by means of a line of stitches 29. These stitches 29 take the place of the lace 15 21 used in the previous forms of the invention and in other respects it is similar to the previous form.

According to the modification shown in Fig. 8, the stitches 29 for connecting the back edge 20 portions of the sections 10^a extend only partially to the bottom of the garment and a slide fastener 30 is provided for connecting the remaining portions of the sections 10^a. In other respects 25 this form of the invention is similar to that described relative to Fig. 7.

While I have illustrated and described the preferred embodiments of my invention, and of the objects and advantages thereof, reference will be had to the following description and accompanying drawings, and to the appended claim in which the various novel features of the invention are more particularly set forth.

Having thus described my invention, what I claim as new, and desire to secure by United States Letters Patent is:

A foundation garment of cloth material having a vertical opening along the median line thereof, the material adjacent each edge of the opening having vertical strips of cloth secured 40 to the inner and outer sides thereof and extending partially across said opening, the upper portion of the free edges of said inner and outer strips being secured together and having separable fastener elements permanently attached thereto for closing the upper portion of the garment, the lower free vertical edge portions of said strips being unconnected, a slide fastener for closing the lower portion of said garment, said slide fastener having stringer elements, and adjustable means normally covered by said strips for connecting the stringer elements of said slide fastener to the lower vertical edge portions of said material, said means comprising rows of eyelets adjacent the edges of 50 said material and said stringers, respectively, and a lacing engageable through said eyelets, whereby the distance between said stringers and said material may be altered for adjusting the circumference of the lower portion of said garment. 55

MARTIN GROSS.
